[57] ABSTRACT

A method and apparatus for printing a plurality of single warp ends of yarn wherein the ends of yarn are passed through a series of printing assemblies, each assembly including a pair of roll-like assemblies at least one of which roll-like assemblies carries a plurality of reciprocally movable pads thereon which can be selectively, reciprocally moved in a pre-determined manner in a direction normal to the longitudinal axis of the roll-like assembly to contact the yarn being printed on. Control of the pads is, in turn, made possible by a plurality of patterned program bars which can be selectively moved in a pre-determined manner in a direction normal to the reciprocal direction of movement of the pads.

FIG. 25.

PRINTING APPARATUS

The present invention relates to a textile printing apparatus and method and more particularly to an apparatus and method useful in dyeing a plurality of single ends of yarn as the plurality of yarns is fed through the apparatus of the invention. The dyeing operation performed on the yarn by this invention may be such as to dye a precise figured pattern on the yarn or to dye a random, so-called space-dye pattern, on the yarn.

The method and apparatus of this invention represent improvements over the method and apparatus disclosed in my prior U.S. application Ser. No. 684,055, now U.S. Pat. No. 3,561,235 covering the apparatus of that application and U.S. application Ser. No. 113,757 covering the method of that application.

A primary object of this invention is the provision of an apparatus and method useful to convert a supply of single ends of undyed yarn to a supply of single ends of dyed yarn.

A more specific object of the invention is the provision of apparatus and a method to dye a pre-determined pattern on single ends of yarn as such yarn is fed through the apparatus of the invention.

A further object of the invention is the provision of apparatus for dyeing as above described wherein the pattern being dyed on the yarn can be varied quite simply and quickly and without costly and time-consuming down-time of the apparatus to effect pattern changes.

A still further object of the invention is to provide a yarn-dyeing apparatus and method wherein the pattern changing operation is limited to a change of a pattern-control sub-mechanism, thereby eliminating the need to change the actual pattern imprinting structure, such as the dye pads of my aforementioned U.S. Pat. No. 3,561,235.

An additional object of this invention is the provision of a yarn-dyeing apparatus and method above described wherein the actual dyeing of the yarns is accomplished by a plurality of endless dye-pad carriers arranged in series.

A still further object of the invention is the provision of apparatus as hereinabove described wherein the endless carriers take the form of rotating roll-like structures, each supporting a plurality of pads movable into operative and non-operative positions by control means, which control means, in turn, are operated in a pre-determined manner.

The above objects and advantages as well as other objects and advantages of the invention will become readily apparent from the following description taken in connection with the accompanying drawings wherein:

FIG. 1 is a side view of apparatus of the instant invention.

FIG. 2 is a section view of a lower roll assembly of the instant invention.

FIG. 2A is a perspective view of a lower roll assembly with associated apparatus.

FIG. 3 is a section view of a portion of the apparatus of FIG. 2 taken along the line 3-3 of FIG. 2.

FIG. 4 is a detail view of a portion of the apparatus of FIG. 3.

FIG. 5 is a detail view of a printer pad assembly.

FIG. 6 is a view of a printing assembly showing details of the traveling carriage assemblies associated with such printing assembly.

FIG. 7 is a perspective view of a portion of the apparatus of FIG. 6.

FIG. 7A is a perspective view of a portion of the apparatus of FIG. 6.

5 FIG. 8 is a view of program bar camming assemblies of an upper and lower roll assembly.

FIG. 9 is a view of the pattern chain mechanism and associated structure controlling the traveling carriage assemblies.

10 FIG. 10 is a view of a modification of program bar assembly, useful in the instant invention.

FIG. 11 is a view taken along the line 11-11 of FIG. 1 and showing a portion of the apparatus of FIG. 1.

15 FIG. 11A is a detail view of the portion of apparatus of FIG. 11.

FIG. 12 is a perspective view of a pressure pad.

FIG. 13 is a view of a program bar assembly.

FIG. 13A is a view of a program bar assembly.

20 FIG. 14 is a section view taken along the line 14-14 of FIG. 13.

FIG. 15 is an exploded view of a portion of the apparatus of FIG. 7.

FIG. 16 is a diagrammatic view showing the cooperation between program bars and associated shifting cams.

FIG. 17 is a perspective view of a portion of apparatus of FIG. 6.

25 FIG. 18 is a detail view of a portion of apparatus of FIG. 17.

FIG. 19 is a diagrammatic view of the program bar shifting cam assembly.

30 FIGS. 20A through 20E are diagrammatic views showing the positions of a printer pad tang relative to its controlling program bar.

FIGS. 21A through 21E are diagrammatic views showing the positions of a printer pad tang relative to its controlling program bar.

35 FIGS. 22 through 24 are side views of pattern chains used to control the shifting of the program bars.

40 FIG. 25 is a diagrammatic view of a phase shifting assembly useful to bring the printing assemblies of the invention into proper pattern registration.

FIG. 1 shows an embodiment of the present invention

45 wherein three printing assemblies generally indicated by the arrows 101, 101a, 101b are utilized. Referring to that figure, the yarn 102, comprising a plurality of single ends, is withdrawn from a creel or beam yarn supply, not shown, by a feed roll assembly, and is, in

50 turn, presented in a well known manner in a sheet like form to a first printing assembly 101 including upper and lower roll assemblies 104 and 105 where a first portion of a pattern to be imprinted on the yarn is printed thereon. The yarn is then moved from the first printing assembly through a guiding, supporting, and feed assembly, comprising a pair of upper and lower rollers 109 and 110 having slats 112, 112a, some of

55 which may be serrated, as for example the slats 112, mounted around the circumference thereof, to the second printing assembly 101a, which is similar to the first such printing assembly and where a second portion of the yarn is printed on the yarn. The yarn is then passed to the third printing assembly 101b where a third portion of the pattern will be printed on the yarn, and finally the yarn 102 is passed to a suitable take-up assembly, not shown. The yarn may be steamed, washed

60 and dried after leaving the final printing assembly.

65

FIG. 5 is a detail view of a printer pad assembly.

The feeding assembly includes a plurality of feed rolls 115, 116, 118, and 119 some or all of which may be driven, and a driven clutch roller 119a which has a surface speed in excess of the aforementioned rollers 115, 116, 118, 119. The yarn 102 is guided through the feeding assembly by a plurality of suitable guide members 120-123, at least one of which, namely the guide member 122, may be suitably mounted so as to be adjustable vertically, FIG. 1, to adjust the tension of the yarn in the stretch between the guide 121 and the roll 116. The construction is such that in the event of increased tension on the yarn, during movement thereof, the yarn will press with greater pressure against the fast running roll 119a and be thereby speeded up to relax the tension.

Although I show three printing assemblies, it is to be understood that the apparatus may incorporate as many printing assemblies as required to obtain the desired pattern, and the number of printing assemblies will normally be dictated by the number of different colors to be incorporated in the pattern. For example, if a six color pattern is to be printed on the yarn, there would normally be six printing assemblies, and, should a seven color pattern be desired, there would then be seven printing assemblies. The embodiment of FIG. 1 is adequate for up to a three color pattern.

Each of the printing assemblies of FIG. 1 includes a lower printing roll and an upper printing roll such as the roll assemblies 104 and 105 above mentioned. The lower printing roll assembly 105 of FIG. 1, cooperates with a dye trough 130 to transfer dye from the dye trough to the yarn, while the upper roll assembly 104 functions as a pressure roll to bear against the pads, hereinafter described, of the lower roll assembly when printing on the yarn, all as more particularly hereinafter described.

Each of the printing assemblies is substantially the same and, within each printing assembly, the two roll assemblies, as for example the upper roll 104 and the lower roll 105 of the first printing assembly 100, are substantially the same in construction and operation, except as hereinafter described and except as the requirements of the apparatus may dictate.

A description of the lower roll assembly of a printing assembly will now be given, this being the lower roll assembly 105b of the third printing assembly 101b of FIG. 1.

The machine framework 117, FIG. 2, supports a dead shaft 135 having an intermediate cylindrically shaped cam portion 136. Near each of its ends, the shaft bearingly supports hubs 137, 137a for rotation about such shaft 135. Each of the hubs has an end plate 139, 140 keyed to it. A plurality of supporting rings, only two of which 141, 142 are shown, are provided.

Each of the rings 141, 142, and each of the two end plates 139, 140 has a plurality of threaded openings spaced circumferentially therearound, and a plurality of multi apertured channel-shaped stringer members 143 extending from end plate to end plate, are secured across the end plates and the rings, each stringer 143 being so secured by a plurality of threaded connectors 144 passing through aligned openings in the sidewalls of the stringer and the end plate or ring, as the case may be, the connectors suitably cooperating with the threaded openings in the end plates and rings. A bearing hub 146 is secured to the cam equipped dead shaft 135, as by shrinking or welding, intermediate its length.

The outer circumferential surface of this bearing member is provided with a bearing material 147 such as nylon, Teflon, or the like, and the ring 141 is supported for rotational movement by this bearing assembly.

In the discussion that follows, use is made of the terms "radially outwardly" and "radially inwardly" in describing the invention. The term "radially outwardly" refers to the direction of a radius extending from the dead shaft 135 toward the stringers 143 while the term "radially inwardly" refers to the direction of a radius extending from the stringers toward the dead shaft. Also, the terms "right side" and "left side" refer to the right side and left side of the roll assembly, printing stations, stringers, program bars, or the like as viewed by an observer looking in the direction of yarn movement, that is looking in the direction of the arrows 150 of FIG. 1. This direction, that is the direction of the arrows 150 of FIG. 1 is hereinafter referred to as the "downstream" direction, the reverse direction, in turn, being referred to as the "upstream" direction.

In the present embodiment of this invention, and for illustration only, I provide 48 such stringers 143 so connected to the end plates and rings of each roll assembly such as the lower roll assembly 105b, the stringers, as shown, being spaced equidistantly circumferentially therearound, and each such stringer has a plurality of aligned pairs of openings formed in its opposed side walls, each aligned pair of openings being provided to receive a printer pad assembly 160 as hereafter described.

A printer pad assembly 160 includes a channel shaped platform portion 161 having a circular pad 162 and a tang 163 extending from one surface of the platform. A slightly flexible cap member 164 is snap fitted over the platform and supports, in turn, in the case of the lower roll assemblies, a resilient pad 165 having secured thereto a pile surface material 166. The flexible pad may be made of polyvinyl chloride foam, while the pile material may be made of polyester. In the case of the upper roll assemblies, I have found it expedient to replace the resilient material and pile surface with a material 167 of low resilience such as a rigid polyvinyl chloride having a serrated exposed surface.

Each of the latter mentioned pairs of aligned openings in the stringers receives a printer pad assembly, the rod thereof extending through such pair of holes for slidable movement in the direction normal to the longitudinal axis of the stringer on which such printer pad assembly is carried. The portion of each such rod remote from its connection to its associated platform carries a spring member 169 constrained between the radially inwardly sidewall of the stringer on which such printer pad is carried and a foot pad 171 secured to the foot of such rod, the spring biasing its associated printer pad assembly in a direction toward what I term a non-print position, that is to say, in a radially inwardly direction toward the central, cam equipped, dead shaft 135.

All of the printer pad assemblies carried on the same one stringer and aligned longitudinally thereof are hereinafter collectively referred to as a row, while any series of printer pad assemblies carried on different stringers and aligned in a plane normal to the axis of the shaft 135 are hereinafter collectively referred to as a column.

The web portion of each stringer member has a somewhat C-shaped carrier member 173 secured

thereto, as by spot-welding or the like, the carrier member extending lengthwise of the stringer and receiving therein, for slidable movement along, an elongated T-shaped program bar 174. The program bar extends lengthwise of the C-shaped carrier and has a main body portion 175 with a centrally extending portion 176 extending at right angles to the main portion. This central portion of each program bar, extending at right angles to its main portion, it will be noted, lies in a plane extending across the path of movement of the tang 163 of each print pad assembly carried on a stringer next adjacent, in the direction of rotation of the roll assembly, to the stringer on which any such program bar is carried. For the present, let it be understood that each program bar controls all the print pad assemblies mounted on such adjacent stringer, and that the program bar controlling the series of printer pad assemblies mounted along any one stringer is the program bar mounted on the stringer next following the controlled row of printer pad assemblies, as the roll assembly rotates.

In the present embodiment I mount, as above mentioned, 48 stringers along with their associated program bars and printer pad assemblies, around the circumference of each roll assembly. This number could, no doubt, be varied, but I have found that 48 provides a convenient size roll assembly to work with. These 48 longitudinally extending rows of printer pad assemblies are divided into two groups, namely a first group, comprising consecutive rows 1 through 24 and a second group comprising consecutive rows 25 through 48. The first group comprises all the rows spaced around one-half of the circumference of the roll assembly, while the second group comprises the balance of the rows spaced around the other half of the circumference of the roll assembly. And, of course, the first group of program bars, that is to say the group of 24 program bars controlling the print pad assemblies of rows 1 through 24, comprises those program bars carried on the stringers carrying print pad rows 2 through 25 while the second group of program bars comprises those bars carried on the stringers carrying print pad rows 26 through 1. In the embodiment shown, in the lower roll assembly 105b under discussion, each program bar controlling the printer pads of the first group has a portion removed from its outboard ends, FIG. 13A, leaving a void radially inward of the longitudinal centerline of such bar, while each program bar controlling printer pads of the second group has a portion removed from its outboard ends, FIG. 13 leaving a void radially outward of the longitudinal centerline of such bar.

The program bars are, as hereinafter described, shifted to and fro within their carriers, along the longitudinal axis thereof as, and for a purpose, described below. Suffice it to say for the present, however, that for each roll assembly there are two separate program bar shifting assemblies to shift the program bars to and fro. One program bar shifting assembly acts on the program bars controlling the printer pad assemblies of the aforementioned first group of printer pad assemblies, while the other program bar shifting assembly acts on and controls those program bars controlling the printer pad assemblies of the second group of printer pad assemblies.

As will be appreciated the program bars as so far described would limit radially inwardly directed spring biased movement of the printer pad assemblies due to

the outwardly extending central portion of each such program bar lying in the path of travel of the tang on each of the printer pad assemblies controlled by that program bar, thus maintaining those printer pad assemblies in their radially outwardly extended, operative, print position. The central portions of the program bars may, however, be notched or voided at certain points therealong, in accordance with a pattern, to permit passage of the tang on certain printer pad assemblies through the area of the outwardly extending portion of its associated program bar, and thus allow each printer pad assembly having its tang aligned with a notched, or voided, portion, of the centrally extending portion of its associated program bar to be moved, by action of the spring 169 mounted on the rod of each such printer pad assembly, bearing against the stringer 143 and the foot pad 171 of such printer pad assembly, to be moved radially inwardly until such movement is limited by abutment of the platform 161 of such printer pad assembly against its supporting stringer 143. For the present, let it be understood that each program bar is notched, as hereinbefore mentioned, according to a pattern; and each such bar may be shifted to and fro along its longitudinal axis, in a pattern, to place, on the one hand, notches formed in its outwardly extending central portion below the tangs of some or all of the printer pad assemblies in the row of printer pad assemblies controlled by such program bar and, on the other hand, to place non-notched portions of the outwardly extending central portion of each such program bar in the path of the tang on some or all of the printer pad assemblies in the row of printer pad assemblies controlled by such program bar.

A fuller description of the programming, i.e., notching, of the program bars will be provided hereinafter.

The dead shaft 135 as previously mentioned, has a portion intermediate its ends forming a 136, and this cam is referred to as a cleaning cam. This cam surface extends a sufficient length of the dead shaft such that its camming surface is contacted by the foot pads of all the printer pad assemblies of a roll assembly during a portion of each revolution of the roll assembly. The cam is in the form of a cylinder whose axis is spaced horizontally, FIG. 3, from the axis of its associated roll assembly. The contour of the cam is such that all the printer pad assemblies controlled by any one program bar of the roll assembly will be maintained in their radially outwardly positions during that portion of every revolution of its roll assembly during which such program bar 174 is shifted to or fro along its carrier 173. Such action, it will be appreciated, ensures clearance of the tangs of the printer pad assemblies from the area of travel of the outwardly extending central portions of their controlling program bars to allow unimpeded shifting movement of the program bars as subsequently described.

Each roll assembly is provided, downstream thereof, with two traveling carriage assemblies generally indicated by the arrows 180 and 181, FIG. 6.

The traveling carriage assembly 180 of FIGS. 6, 7, and 17 is representative and acts, as hereinafter described, on the program bars controlling the second group of printer pad assemblies, to shift such program bars to and fro along their carriers, while the assembly 181 acts on the program bars controlling the first group of printer pad assemblies.

The carriage assembly 180 includes a shaft 182 journaled for sliding movement to and fro in suitable bearing assemblies carried on bracket members 183a - 186a, respectively, carried on the machine framework 117. The shaft 182 is rigidly secured to a plate assembly 190 which is connected to a slidably mounted follower 192, which follower cradles a plurality of lugs 193 carried on a lug disc 194 carried on a dead shaft 226. The plate assembly 190, it will be noted, is in turn rigidly connected to a slidable shaft 182a of an upper roll carriage assembly 180a.

A first stub shaft 196, spaced downstream of and in the same horizontal plane as the shaft 182, is slidably supported in bearings carried on the bracket members 183a, 184a, and a second stub shaft 197 is similarly slidably supported in bearings carried on brackets 185a, 186a. The stub shafts 196 and 197 are appropriately inter-connected to the shaft 182 by means of a spanners, such as the spanner 199 shown in FIG. 17 so that as the shaft 182 moves to and fro, as hereinafter described, so too will the stub shafts.

A cam block 200 is secured to the shafts 182 and 196 to move in unison therewith.

This block 200 supports a cam assembly carried by the traveling carriage assembly 180 and is similar to a corresponding block 200a supporting a cam assembly and carried on the traveling carriage assembly 181. A representative block and cam assembly is shown in detail in FIG. 15.

The block 200a of FIG. 15 has a channel 201a which receives a bar 202a carrying a cam shoe 203a and cam 204a. The bar slidably movable and may be secured in place by an adjusting member 206a. The adjusting member 206a extends through a slot 208a in the cover 209a of the block 200a and is threaded into the bar 202a, the construction being such that the bar 202a can be moved along the channel 201a, FIG. 15, to the extent allowed by the length of the slot in the cover member 209a, and then locked in position by tightening the adjusting member 206a.

The traveling carriage assembly 180 carries a block and cam assembly, similar to that just described, at each of its ends, FIG. 6, as does the assembly 181. Further, each roll assembly of each printing assembly, for example the first, second and third printing assemblies of FIG. 1, is equipped with two similar traveling carriage assemblies. Also, the traveling carriage assembly controlling the first group program bars of the lower roll assembly of a printing assembly is interconnected with the traveling carriage assembly controlling the first group program bars of the upper roll assembly of that printing assembly, and the two move in unison. The carriage assembly controlling the second group program bars of the lower roll assembly is interconnected with the carriage assembly controlling the second group program bars of the upper roll assembly.

Each of the cams such as the cam 204a carried on the traveling carriage assembly 181, FIG. 7, has a cam surface 204b and a dwell surface 204c complementing the cam surface and dwell surface of the other cam of the pair as shown in FIG. 16. The distance between the dwell surfaces of a complementary pair of cams is very slightly more than the overall length of the program bars shifted by such pair of cams.

Movement of the traveling carriage assembly 180 of FIGS. 6 and 17 is caused by an oscillating lug disc, the aforementioned disc 194, which carries the plurality of

lugs 193 and cooperates with the aforementioned lug follower 192 secured to the shaft 182, through the plate assembly 190, of the traveling carriage assembly 180.

Oscillation of the lug disc is controlled by a pattern chain assembly, FIGS. 2A, 6, and 9. The pattern chain assembly includes a rotating driven disc 214 having a contoured cam surface formed by a pattern chain 215. A rocker arm 216 having a cam follower 217 is mounted for rocking movement on a shaft 218 carried in the machine framework 117. At its end remote from the cam follower, the rocker arm is suitably coupled to a connecting rod 220 which, in turn, at its end remote from the connection with the rocker arm 216, is suitably clamped to an oscillatory shaft 221 such that, upon rocking movement of the rocker bar 216 in response to rotational movement of the pattern chain 215, the shaft 221 will be oscillated.

The oscillatory shaft 221 has a sprocket wheel 224 keyed thereto. A sprocket wheel 225 is loosely carried as between collars on the dead shaft 226 carrying the aforementioned lug disc 194, and such wheel is coupled to the disc 194. Additionally, an idler sprocket wheel 227 is carried on the machine framework. An endless chain 230 is trained around all three of these sprocket wheels 224, 225, and 227, and will it be appreciated therefore, that, as the pattern chain 215 moves and rocks the rocker arm 216, such movement of the rocker arm will be transmitted to the lug disc 194 to thereby rotate the disc and move the lug follower 192 and its connected traveling carriage 180 to and fro in directions paralleling the longitudinal axis of the roll assembly. Such action causes the pair of cams carried on such carriage, one cam at each end thereof, as above mentioned, to likewise move, and thereby allow shifting of the program bars controlling the printer pad assemblies of the second group of the rotating roll assembly, it being remembered that, as any program bar enters the area of the shifting cams, the printer pad assemblies controlled by such bar are in their radially outward position.

After any given program bar is shifted by its cams, the printer pad assemblies controlled by that program bar ride off the high run of the fixed clearing cam 136 to allow the tangs of those printer pads aligned with a notch or void in such program bar to pass through such notch, to simultaneously position such printer pad assemblies in their radially inwardly non-operating, non-printing position, and thereafter, such printer pad assemblies will now be in position for the succeeding pass through the printing zone, that is, the area where the pad assemblies of the lower and upper roll assemblies contact the yarn, the shifting operation of the program bars again being repeated when such row of printer pad assemblies again move into cooperating relationship with the clearing cam, the shifting cams, etc.

The other traveling carriage assembly 181 associated with the first group of program bars of the lower roll, and its mode of operation, is substantially the same as that described in relation to the first traveling carriage assembly 180. This other carriage 181, however, is controlled by a second disc 214a and pattern chain 215a assembly acting on similar linkage to oscillate a shaft 221a, etc.

It will be appreciated that the carriage assembly 181 cannot act upon the program bars controlling the second group of printer pad assemblies, this due to the dif-

ferent cut-outs of the end portions of those program bars, nor can the carriage assembly 180 act on the first group of program bars, because the cams of carriage assembly 181 are spaced radially outwardly of the cams of carriage assembly 180.

The pattern chains 215, 215a are contoured the same but are out of phase, with the chain 215 that is, the chain controlling the second group program bars, lagging the chain 215a. Thus the second group program bars follow exactly the shifting movement of the first group of program bars. For example, the first group bars will be cammed such that their respective ends lie in the same plane after the last bar of the group leaves the area of their associated shifting cams, and, immediately following, the second group bars are similarly aligned by their cams in the same plane. Thus, during each revolution the entire 48 program bars of the roll assembly 105b under discussion will pass through the printing zone with their respective outer ends aligned in the same plane. Further, as will become apparent in the description that follows, in a multi-printing assembly, for example, the three printing assembly embodiment of FIG. 1, all the program bars of both roll assemblies of each printing assembly will pass through their printing zones, during each revolution, with their respective outer ends aligned in the same plane.

The reason I prefer to use two separate pairs of cams, one pair to control the program bars of the first group, and the other pair to control the program bars of the second group, is that I prefer to use relatively long cams and, since the program bars may be shifted once each revolution of the roll assembly, I desire to avoid the necessity of making abrupt shifting movement of short cams. If there were only one carriage assembly to control all the program bars of a roll assembly, I would be faced with the necessity of having to use short cams and shifting such short cams during the period encompassed in not more than one forty-eighth of a revolution of the roll assembly. By using two carriages with their associated cams, I have a much longer period in which to shift any pair of cams. For example, the pair of cams controlling the program bars of the first group may be shifted during the relatively long interval occurring between the time the program bar controlling the 24th row leaves the dwell of such cams and the time the program bar controlling the first row reaches the leading edge of such cams. Similarly the other pair of cams controlling the program bars of the second group is shifted during the period between the time when the program bar controlling the 48th row leaves the trailing edge of such other cams and the time when the program bar controlling the 25th row reaches the leading edge of such other cams.

I could, however, use only one traveling carriage assembly with a cam at each end to control shifting movement of all the program bars of a roll assembly. In such a case, the overall length of the cam carried at each end of the carriage assembly would be of a length less than the distance between two adjacent program bars and it would have to be shifted rather abruptly. In this case, each roll assembly would be equipped with one traveling carriage assembly and all such carriages would move in unison under control of a pattern chain such as the chain 215, for example, and the cams could be shifted during each revolution of the roll assembly, from any given position to a new position after the forty-eighth program bar leaves the dwell and before

the first program bar reaches the leading edge of the cam surface thereof.

In each printing assembly the lower and upper roll assemblies are, as above mentioned, substantially identical. That is, each roll assembly has the same number of longitudinally extending rows of printer pad assemblies spaced circumferentially therearound, and each such row has the associated structure, modified as necessary, previously described. Further, the traveling carriage assemblies associated with the lower roll of any given printing assembly are coupled to and moved simultaneously with the corresponding traveling carriage assemblies associated with the upper roll. That is to say, the traveling carriage assembly and associated cams controlling the first group program bars of the lower roll is coupled to the traveling carriage assembly controlling the first group program bars of the upper roll assembly, and the traveling carriage assembly controlling the second group program bars of the lower roll is coupled to and travels with the traveling carriage assembly controlling the second group program bars of the upper roll.

Also, the traveling carriage assemblies controlling the first group program bars of the upper and lower rolls of all printing assemblies are coupled for movement in unison, and the carriage assemblies controlling the second group program bars of each roll assembly are similarly coupled for movement in unison. Such coupling is accomplished through suitable sprocket and chain means, not shown, operatively connected to the oscillatory shafts 221, 221a, which shafts are supported by and extend the length of the machine framework 117, from the first printing station to the last printing station, FIG. 1.

As above mentioned, the program bars controlling the first group of pads of the lower roll assembly are notched at their ends, radially inward of the central portions while those controlling the second group are notched, at their ends, radially outward of their central portions. This holds true for the lower roll assembly, and it could hold true for the upper roll, but I prefer to notch the first group bars of the upper roll assembly radially outward and those of the second group of the upper roll assembly radially inward. Thus it will be appreciated that, with reference to FIGS. 6, 8, and 19, the shafts 182 and 182a are coupled together for shifting movement in unison, as are the corresponding shafts of the carriage assemblies 181 and 181a.

The program bars of the upper and lower roll are consecutively numbered 1 through 48 and the roll assemblies are phased so that the row of printer pads controlled by the number one program bar of the lower roll assembly will meet and bear against the pads controlled by the number one program bar of the upper roll assembly at the printing zone. So too will the pads controlled by the second through 48 bars of each lower roll assembly meet and bear against their corresponding upper roll pads. The two bars comprising each pair, for example the number one bar of the lower roll and the number one bar of the upper roll, are notched along their respective centrally extending portions 176 according to the same pattern.

A discussion will be hereafter given relating to the notching of the program bars but for the present, I trust it will be apparent that I have provided a printing assembly wherein upon each rotation of the two roll assemblies of one printing assembly I can print, upon a

plurality of separate warp ends of yarn up to a 48 unit repeat pattern. Subsequently, due to the fact that I am able to re-position, by shifting movement of the traveling carriage assemblies, the notched program bars once during each rotation, I can again print another pattern having a different 48 unit repeat for a total of a 96 unit repeat. Thence, by again shifting the program bars I can print an additional new 48 unit repeat for a total of a 144 unit repeat.

In the present embodiment, the horizontally extending portion 176 of each program bar is divided into equal length portions, and one such portion is allotted for the control of each printer pad assembly. Each such portion is further divided into eight segments and each such segment can be selectively positioned, by the associated carriage assembly, in alignment with its associated tang to control the printer pad assembly carrying such tang. Thus, each program bar is shifted to and fro along its longitudinal axis by its associated carriage assembly to effectively control its controlled row of printer pad assemblies.

Each program bar has what I term a home or wash position. This position is the position it is in when it shifted full rightward of the machine. Whenever a program bar is in its home or wash position, it places a notched portion of its central portion 176 aligned with the tang of each printer pad assembly in its controlled row, thus the wash position cannot be utilized for printing, since, whenever a program bar is in wash position all the pad assemblies controlled by that bar will be allowed to be retracted to their radially inward, non-print position.

The purpose of the wash position is to allow all the printer pad assemblies of each printing assembly to be retracted to their radially inwardly position, thus allowing the two roll assemblies of each printing assembly to rotate without sandwiching the yarn therebetween. This allows the pads to be washed down by water or any other appropriate washing vehicle through spray means 235, diagrammatically shown in FIG. 3, located in proximity to the roll assemblies, and supplied with liquid from any suitable supply source, not shown.

Thus, keeping the above in mind, each program bar has, in the present embodiment, one wash position and seven print control positions for controlling each printer pad assembly controlled by it. In FIGS. 20A through 20E I illustrate diagrammatically a portion of a typical program bar 174, which is representative of a set of program bars of a printing assembly, having a wash control segment 240 and seven print control segments 241 through 247. Each program bar, of course, has a multiplicity of such portions extending therewith. These figures, i.e., 20A - 20E are viewed in a downstream direction with the program bar 174 at top dead center of the lower roll assembly 105b under discussion, and it will be noted, with reference to FIG. 20A, that the bar 174 is full rightward with its wash segment 240 aligned with the tang 163. The bar 174 of FIG. 20A is shifted relative to the tang 163 by means of its associated pattern chain 215 or 215a as the case may be.

The chains 215, 215a, incidentally, in the present embodiment, are divided into a predetermined number of equal length cam segments along their length. The number of segments is a function of the number of units in the pattern repeat divided by 48. Thus, for example, a 96 unit repeat pattern would require at least a two

segment chain and a 336 unit repeat would require at least a seven segment chain and, in fact, I use chains having a six, six, eight, 10 six, and 14 equal length cam segments for printing patterns having repeat lengths of 96, 144, 192, 240, 288, and 336 units, respectively. Each equal length cam segment of chain, see FIGS. 22-24, it will be noted, is four links in length and the relationship between the discs and roll assemblies is such that four links of the chain move past the cam follower 217 each time a roll assembly makes a complete revolution. The chains 215, 215a may be supported solely on the discs 214, 214a, or when the chains are of a length longer than the disc circumference, they may be trained around adjustable idler sprockets 215k and the discs, as shown in FIGS. 22 and 24. FIGS. 23, 22, 24 show pattern chains used when printing patterns having a repeat length of 96 units, 192 units, and 336 units, respectively. The chain and the roll assemblies are phased such that the chain presents a succeeding segment to the rocker arm 216 follower 217 for each revolution of the roll assembly. One such segment such as the segment 215b, FIGS. 2A, 9, of the chain 215 allows the shifting of its associated program bars to two positions. It will be noted that the end 216a of the rocker arm 216 rests atop a pin 217a slidably carried on the machine framework 117. So long as the pin 217a underlies the end 216a of the rocker arm 216, the roller 217 is prevented from dropping into the low dwell of segment 215b on the chain 215. When it is desired to cause the roller 217 to drop into the low dwell of the segment 215b of the chain 215, the pin 217a is moved out of underlying relationship with the end 216a, allowing the roller to drop to its lowermost extent. When the roller is in this latter position, the program bars controlled by the chain 215 are cammed to their wash position, and, through any suitable interlock or switching means, the dropping of the roller to its lowest position causes the disc 214 to stop rotating, thereby causing all the printer pad assemblies controlled from such chain to eventually be positioned in their radially inward position so as to not sandwich the yarn during continued rotation of the roll assemblies. Further, the dropping of the roller to its lowest position can be utilized to activate any suitable switching means to shut down, after a period of time, for example the time required for the roll assemblies to make one complete revolution, the entire machine assembly, and apply any suitable brake means, not shown, to the feed rolls to inhibit yarn from being withdrawn from the yarn supply while the apparatus is in the wash condition. At this point, suitable driving means can be activated to rotate the printer pad assemblies so that they can be washed by the spray means 235.

When the pin 217a is in position as shown in FIG. 2A, the program bar 174 of FIG. 20A will be positioned so that its segment 241 is aligned with the tang 163, and I normally contour the pattern chains 215, 215a so that any program bar is always shifted from its wash position to a position two segments away, such that its segment 242 will be aligned with the tang 163.

Thus, the pattern chains 215, 215a have one control segment which serves to position their controlled program bars in two different positions depending on whether the pin 217a is or is not in underlying relationship with the end 216a of the rocker arm 216, and in the present embodiment of the invention, the segment of pattern chain that allows the program bar to be posi-

tioned with its print control segment 241 in alignment with its associated tang when the pin 217a is in the aforementioned underlying relationship, is the same segment of chain which allows the program bar to be positioned with its wash segment 240 in alignment with its associated tang when the pin 217a is moved out of such underlying relationship. It will thus be appreciated that when a program bar moves out of wash position it will normally move to a position such that the control segment of the program bar, that is normally aligned with the tang 163 after the control segment 241 is aligned, will be aligned with the tang.

From the above, it will be appreciated that, during printing operations, the program bars are normally shifted to any one of seven different print positions, and that they go to their eighth or wash position only during the wash cycle.

Although the program bars can be shifted to seven different positions, in addition to the wash position, relative to the tangs of their controlled printer pad assemblies, it should be understood that the number of different positions to which they are shifted will normally be a function of the number of units in the pattern repeat. For example, if the pattern repeat length is 48 units or less, it would not be necessary to shift the program bars at any time, except from a printing position to the wash position. Should the repeat length be ninety-six units, the program bars would need to be shifted to two of the seven different printing positions, and so on, until, if the repeat length were 336 units, the program bars would need to be shifted to all of the seven printing positions during printing operation of the machine.

Referring again FIGS. 20A through 20E, and keeping in mind what has been previously set forth, I show, diagrammatically, a portion of one of the program bars 174 which would be used to control the printer pad assemblies of a roll assembly printing a 96 unit repeat. As previously mentioned each tang control segment of this bar has a wash segment 240 and seven print segments 241 - 247. In this case, forgetting for the present the wash position, only the print segments 241, 242 would need be used, and all 48 program bars utilized on a given roll assembly would be similarly used, that is, each would utilize only two print segments and each need be shifted only from a first position to a second position, thence back to the first position and so on. The absence or presence of a notch in the bars in the segments 242 would, for example, control the printing on the warp ends passing through the printing zone during a given revolution of the roll assembly. Then, during the subsequent revolution, the bars having been shifted to place the print segments 241 of each bar under the tangs, the absence or presence of a notch in such segments would control the printing on the same warp ends during such subsequent revolution.

During the next revolution, the bars would be in the position shown in FIG. 20D corresponding to that of FIG. 20B, and during the succeeding revolution, the bars would be in the position shown in FIG. 20E, corresponding to the FIG. 20C position.

As above mentioned, all the program bars of all the roll assemblies have their respective outer ends aligned in the same plane as they pass through their respective printing zones during each revolution. Further, it will be appreciated that, in the case of a 96 unit repeat pattern, when the first row of the pattern is being printed at the first printing assembly of FIG. 1, the forty-ninth

row will be being printed at the second printing assembly, and simultaneously, the first row will be being printed at the third printing assembly. This is due to the fact that, in the present embodiment, the printing zone of each printing assembly is spaced, linearly, from the adjacent printing zone, a distance equal to 48 rows, to obtain proper pattern registration. To accommodate this situation, in the case of, for example, a 96 unit repeat, I utilize that segment of the program bars of the second printing assembly, for controlling the 49th through 96th pattern units printed by the second printing assembly, which are located in the portion of program bar length corresponding to the portion of program bar length controlling lines 1 through 48 at the first printing assembly, and the segments controlling the first through 48th pattern units at the second printing assembly are located in the portion of program bar length corresponding to the portion of bar length controlling lines 49 through 96 at the first printing assembly. Thus, for example, considering a 96 unit repeat if the program bar 174 as represented in FIGS. 20B - 20E is taken as being representative of those of the first printing assembly as positioned for four successive passes, for example, the first through fourth, through the printing zone of the first printing assembly to control the printing of lines 1 through 48, FIG. 20B, lines 49 through 96, FIG. 20C; lines 1 through 48, FIG. 20C; and lines 49 through 96, FIG. 20D; thence referring to FIGS. 21B - 21E and considering the program bar 174 therein shown as being representative of those of the second printing assembly as positioned for the same, i.e., the first through fourth successive passes through the printing zone of the second printing assembly, it will be noted that the alignment of the bars with their tangs is identical in each case. However, the second printing assembly bars of FIG. 21B are, during the first revolution, controlling the printing for lines 49 through 96 of the repeat. In FIG. 21C they are controlling the printing of lines 1 through 48, while in FIGS. 21D and 21E they are controlling lines 49 through 96 and 1 through 49, respectively.

I have found that it is desirable to shift the program bars in not unduly large increments. Thus, for example, if I have a 336 unit repeat, and forgetting the wash zone for the present, I could step the bars in one control segment increments from right to left until the bars were full leftward, thence back in one step, a full seven control segments rightward, and so on. I prefer, however, to contour my pattern chains 215, 215a such that the bars need not be stepped more than two or three control segments during any one shifting movement. For example a program bar such as the bar 174 of FIG. 20A would be shifted such that the segments 241, 242, 244, 246, 247, 245, and 243 control lines 1-48, 49-96, 97-144, 145-192, 193-240, 241-288, and 289-336, respectively, the shifting of the bars being appropriately controlled, as above mentioned, by suitable contouring of the respective pattern chains 215, 215a.

Scrambling of the control zones can be provided on program bars utilized in multi-printing assembly installations to control patterns having a repeat of more than 96 units, as desired, it being kept in mind that such scrambling will be a function of the desired shifting sequence of the program bars and the number of units in the pattern repeat. For example, considering the printing of a pattern having a 336 unit repeat, and assuming that the sequence of shifting of the program bars of the

printing assemblies, by their cams, is, as above mentioned, such that the program bars are shifted to, sequentially, align, with their associated tangs, their segments 241, 242, 244, 246, 247, 245 and 243 to control respectively, lines 1-48, 49-96, 97-144, 145-192, 193-240, 241-288, and 289-336 at the first printing assembly, during successive rotations of the first printing assembly roll assemblies, a table could be constructed as follows to determine which lines of the pattern would be controlled at the second through seventh printing assemblies by the control segments 241, 242, 244, 246, 247, 245 and 243, during corresponding rotations, of the roll assemblies at the second through seventh printing assemblies.

The table would be as follows:

Printing assembly number	Control segment of each control portion of program bar aligned with tangs of printer pad assemblies passing through printing zone						
	241	242	244	246	247	245	243
1st	A	B	C	D	E	F	G
2nd	G	A	B	C	D	E	F
3rd	F	G	A	B	C	D	E
4th	E	F	G	A	B	C	D
5th	D	E	F	G	A	B	C
6th	C	D	E	F	G	A	B
7th	B	C	D	E	F	G	A

where A represents lines 1-48 of the pattern, B represents lines 49-96 of the pattern, C represents lines 97-144 of the pattern, D represents lines 145-192 of the pattern, E represents lines 193-240 of the pattern, F represents lines 241-288 of the pattern, and G represents lines 289-336 of the pattern, and, of course, by referring to such table, the proper scrambling of the notches could be determined for the various program bars by reconstructing the table as follows:

Assembly number	Program bar						
	241	242	243	244	245	246	247
1st	A	B	G	C	F	D	E
2nd	G	A	F	B	E	C	D
3rd	F	G	E	A	D	B	C
4th	E	F	D	G	C	A	B
5th	D	E	C	F	B	G	A
6th	C	D	B	E	A	F	G
7th	B	C	A	D	G	E	F

and, thence, for example, with respect to the program bars for each printing assembly, by notching or not notching therealong the program bar segments 241, 242, 243, 244, 245, 246 and 247 of each bar depending on whether it is desired to not print or print, respectively, at corresponding locations along the row controlled by any such program bar segment, keeping in mind the rows of the pattern represented by A through G as previously discussed.

In FIG. 10 I illustrate a modification of the program bar mounting assembly. Here the program bar 174a controlling a row of printer pad assemblies is carried on the same stringer 143a as the row of controlled pads. The stringer is upset at positions therealong to form a channel to retain the program bar for sliding movement therealong, two such upset portions 143b being shown. Notches, not shown, would be provided at the outboard ends of this bar 174a as with the bars 174 previously described if two sets of shifting cams are used.

The apparatus is provided with a suitably driven main drive shaft 117a and, though any suitable gearing, the roll assemblies, the yarn feeding assemblies and the pattern discs controlling the traveling carriage assem-

blies may be appropriately driven as hereinabove described. The drive train connecting the main shaft to the various roll assemblies includes, for each pair of roll assemblies a shaft 117b, and the drive trains of all printing assemblies, except the first such printing assembly, utilize a phase shifting assembly such as that shown in FIG. 25, which is useful in obtaining proper registration of the pattern printed at the various printing assemblies. The phase shifting assembly includes a take-off 10 sprocket wheel 117c suitably geared to the main shaft 117a and coupled to a dual sprocket wheel 117d, supported on the machine framework, by an endless chain 117e trained therearound. A plurality of additional sprocket wheels 117f, 117g, 117h, and 117j are provided, the wheels 117f and 117g being supported on

the framework and the wheels 117h and 117j being mounted on a adjustable jack 117k operatively movably connected to a threaded member 117l supported on a gear block 117m carried on the machine framework and suitably coupled to a rotatable handwheel 117n, such that upon rotation of the handwheel 117n the jack 117k can be raised or lowered. An endless chain 117p is trained around the wheels 117b, 117d, 30 117f, 117g, 117h and 117j, and it will be appreciated

35

that, in the event the roll assemblies at any printing assembly have to be advanced or retarded to bring them into phase with the roll assemblies of the first printing assembly, such can be readily accomplished, as the case may require, by rotating the handwheel 117n at 50 that printing assembly to thereby raise or lower the sprocket wheels 117h and 117j to advance or retard the shaft 117b of such printing assembly drive train, to thereby bring the roll assemblies thereof into phase with roll assemblies of the first printing assembly.

55 The operating sequence of the apparatus will now be described, with reference to FIG. 1. Assuming that the desired sets of properly notched program bars have been installed in each of the roll assemblies utilized in the first, second and third printing assemblies, and that 60 each of the dye troughs such as the dye trough 130 have a sufficient supply of the proper color dye, the yarn will be fed by the yarn feeding apparatus to the first printing assembly 101 and, as the yarn passes through the printing zone of that assembly, it will be 65 printed upon between the printer pad assemblies of the lower roll and the pressure pads of the upper roll, according to the pattern of notches set up on the program

bars of that assembly. If we assume that we are printing a pattern having a 96 unit repeat, and that the row just printed was the first row of the 96 unit repeat, then as the yarn continues passing through the printing zone of the printing assembly, it will, seriatim, have imprinted thereon the first 48 rows of the pattern repeat and printing or non-printing will occur in each row in accordance with whether there is not or is a notch in each program bar in alignment with the tang of each printer pad assembly and pressure pad assembly passing through the printing zone. All of the program bars 1 through 48 of each roll assembly will pass through the printing zone in the same alignment during each revolution.

After the program bars 1 through 48 pass through the printing zone during this first revolution, they will subsequently be cammed by their respectively associated traveling carriage assemblies into position for printing rows 49 through 96 of the pattern repeat, and as they pass through the printing zone on the second revolution, they will print such rows, again in accordance with the presence or absence of notches in the program bars.

While rows 49 through 96 are being printed at the first printing assembly the yarn will advance towards the second printing assembly and during such advance it will be guided, supported, and fed by the intermeshing slats carried on the rolls 109, 110. At the time the 49th row is being printed at the first printing assembly, it will be appreciated that the previously imprinted first row of the pattern will have arrived at the printing zone of the second printing station and, row one will be imprinted, with a different color dye than was imprinted at the first printing assembly by those pads not having tangs aligned with notches in their controlling program bars. Thus, if we assume that the colors red, green, and blue are being printed at the first, second, and third printing assemblies, respectively, when the yarn containing rows 1 through 48 leaves the first printing zone it will have imprinted thereon all the desired red areas of such rows and, when such yarn leaves the second printing assembly, rows 1 through 48 will have had added to them the desired green areas.

As the leading row of the pattern repeat advances past the second printing assembly and towards the third printing assembly, it will again be supported, guided, and fed by the pair of rolls similar to the aforementioned rolls 109, 110 and, when row one reaches the printing zone of the third printing assembly, row 49 will have reached the printing zone of the second printing assembly and row 1 will again be being printed at the first printing assembly.

As the leading and successive rows pass through the third printing assembly printing zone, the desired blue areas of such rows will be imprinted, and as the yarn passes out of the third printing zone, the pattern will be complete, whereupon the yarn will progress to the aforementioned suitable take-up assembly.

As above described, any suitable arrangement can be utilized to drive the driven parts of the assembly, it being kept in mind that all the roll assemblies of each printing station are driven at a constant speed. A corresponding relationship exists between the surface speed of the roll assemblies and the feed rolls, with the exception of the feed roll 119a which, as previously mentioned, has a surface speed greater than the surface speed of the feed rolls 115, 116, 118, and 119. Further,

I drive the rolls 109, 110 at a speed such that their surface speed will be a bit greater than the surface speed of the roll assemblies.

By way of example, it may be possible to replace the present embodiment of the upper roll assembly with a roll having a unitary pressure surface, i.e., no movable pads. Also the possibility exists that instead of roll assemblies, endless carriers in the form of flexible chains might be used. Further, although in connection with the present embodiment I teach the printing on a plurality of single ends of yarn, the invention would be useful in the printing art generally. Additionally, it may be desirable in some instances to utilize only lower roll assemblies should they, in various applications, prove adequate.

Thus, although in the instant disclosure I have shown a preferred embodiment of my invention, a range of alteration, modification, change, and substitution is intended therein and in some instances some features of the invention will be utilized without a corresponding use of other features. Accordingly, it is intended that the claims be construed in a manner consistent with the full range of the spirit and scope of the invention herein.

Having thus described the invention, I claim:

1. Printing apparatus comprising a printing assembly including at least two carriers, each of said carriers carrying a plurality of pad assemblies thereon movable to a first printing position and to a second non-print position and a plurality of program bars carried on each said carrier, said program bars being movable to control the movement of said pad assemblies.

2. The invention of claim 1 wherein said program bars are movable at right angles to direction of movement of said pad assemblies.

3. The invention of claim 2 wherein said program bars are controlled in their movement by cam means movable to move said program bars relative to said pad assemblies.

4. The invention of claim 3 wherein said carriers are rotating roll assemblies, said plurality of pad assemblies are arranged in rows spaced circumferentially around said roll assemblies, and said program bars are spaced circumferentially around said roll assemblies.

45 5. The invention of claim 4 wherein the number of program bars is equal to the number of rows of pad assemblies.

6. The invention of claim 5 wherein the pad assemblies of each one row are carried on a stringer extending longitudinally of said row.

7. The invention of claim 6 wherein one program bar controls the pad assemblies of one row.

8. The invention of claim 7 wherein each said one program bar is carried on a stringer supporting a row 55 of pad assemblies adjacent to the row of pad assemblies controlled by said program bar.

9. The invention of claim 8 wherein said cam means includes a first cam means to move some of said program bars and a second cam means to move other of said program bars.

10. The invention of claim 9 wherein control means are provided to move said cam means according to a predetermined sequence.

65 11. The invention of claim 10 wherein each of said program bars comprises a first base portion, and a second portion extending at right angles to said base portion, and wherein said second portion extends in a di-

rection to underlie the pad assemblies controlled by each said program bar.

12. The invention of claim 11 wherein each said pad assembly includes a tang movable in a plane intersecting said second portion of the program bar controlling each said pad assembly.

13. The invention of claim 12 wherein each said pad assembly comprises a platform having a rod portion slidably engaged with the stringer supporting said each said pad assembly.

14. The invention of claim 13 including a plurality of such printing assemblies each spaced from the other, and wherein program bars of all of said assemblies are moved by common control means.

15. The invention of claim 14 wherein said program bars are notched along their central portion according to a predetermined pattern.

16. The invention of claim 15 wherein said control means is operative to move said program bars in a first loop having n positions and in a second loop having $n+1$ positions.

17. The invention of claim 7 wherein each said one program bar is carried on the stringer supporting the row of pad assemblies controlled by said program bar.

18. The invention of claim 17 wherein said cam means includes a first cam means to move some of said program bars and a second cam means to move other of said program bars.

19. The invention of claim 18 wherein control means are provided to move said cam means according to a predetermined sequence.

20. The invention of claim 19 wherein each of said program bars comprises a first base portion, and a second portion extending at right angles to said base portion, and wherein said second portion extends in a direction to underlie the pad assemblies controlled by each said program bar.

21. The invention of claim 20 wherein each said pad assembly includes a tang movable in a plane intersecting said second portion of the program bar controlling each said pad assembly.

22. The invention of claim 21 wherein each said pad assembly comprises a platform having a rod portion slidably engaged with the stringer supporting said each said pad assembly.

23. The invention of claim 22 including a plurality of such printing assemblies each spaced from the other, and wherein program bars of all of said assemblies are moved by common control means.

24. The invention of claim 23 wherein said program bars are notched along their central portion according to a predetermined pattern.

25. The invention of claim 24 wherein said control means is operative to move said program bars in a first loop having n positions and in a second loop having $n+1$ positions.

26. Printing apparatus comprising a printing assembly including at least one carrier, said carrier carrying a plurality of pad assemblies thereon movable to a first printing position and to a second non-print position and a plurality of program bars carried on said carrier, said program bars being movable to control the movement of said pad assemblies.

27. The invention of claim 26 wherein said program bars are movable at right angles to direction of movement of said pad assemblies.

28. The invention of claim 27 wherein said program bars are controlled in their movement by cam means movable to move said program bars relative to said pad assemblies.

29. The invention of claim 28 wherein said carrier is a rotating roll assembly, said plurality of pad assemblies are arranged in rows spaced circumferentially around said roll assembly, and said program bars are spaced circumferentially around said roll assembly.

30. The invention of claim 29 wherein the number of program bars is equal to the number of rows of pad assemblies.

31. The invention of claim 30 wherein the pad assemblies of each one row are carried on a stringer extending longitudinally of said row.

32. The invention of claim 31 wherein one program bar controls the pad assemblies of one row.

33. The invention of claim 32 wherein each said one program bar is carried on a stringer supporting a row of pad assemblies adjacent to the row of pad assemblies controlled by said program bar.

34. The invention of claim 33 wherein said cam means includes a first cam means to move some of said program bars and a second cam means to move other of said program bars.

35. The invention of claim 34 wherein control means are provided to move said cam means according to a predetermined sequence.

36. The invention of claim 35 wherein each of said program bars comprises a first base portion, and a second portion extending at right angles to said base portion, and wherein said second portion extends in a direction to underlie the pad assemblies controlled by each said program bar.

37. The invention of claim 36 wherein each said pad assembly includes a tang movable in a plane intersecting said second portion of the program bar controlling each said pad assembly.

38. The invention of claim 37 wherein each said pad assembly comprises a platform having a rod portion slidably engaged with the stringer supporting said each said pad assembly.

39. The invention of claim 38 including a plurality of such printing assemblies each spaced from the other, and wherein program bars of all of said assemblies are moved by common control means.

40. The invention of claim 39 wherein said program bars are notched along their central portion according to a predetermined pattern.

41. The invention of claim 40 wherein said control means is operative to move said program bars in a first loop having n positions and in a second loop having $n+1$ positions.

42. The invention of claim 32 wherein each said one program bar is carried on the stringer supporting the row of pad assemblies controlled by said program bar.

43. The invention of claim 42 wherein said cam means includes a first cam means to move some of said program bars and a second cam means to move other of said program bars.

44. The invention of claim 43 wherein control means are provided to move said cam means according to a predetermined sequence.

45. The invention of claim 44 wherein each of said program bars comprises a first base portion, and a second portion extending at right angles to said base portion.

tion, and wherein said second portion extends in a direction to underlie the pad assemblies controlled by each said program bar.

46. The invention of claim 45 wherein each said pad assembly includes a tang movable in a plane intersecting said second portion of the program bar controlling each said pad assembly.

47. The invention of claim 46 wherein each said pad assembly comprises a platform having a rod portion slidably engaged with the stringer supporting said each said pad assembly.

48. The invention of claim 47 including a plurality of such printing assemblies each spaced from the other, and wherein program bars of all of said assemblies are moved by common control means.

49. The invention of claim 48 wherein said program bars are notched along their central portion according to a predetermined pattern.

50. The invention of claim 49 wherein said control means is operative to move said program bars in a first loop having n positions and in a second loop having $n+1$ positions.
